Specification for Design.

Patented May 5, 1914.

Application filed March 12, 1913. Serial No. 753,848. Term of patent 14 years.

To all whom it may concern:

Be it known that I, ALEXIS R. PRIBIL, a citizen of the United States of America, residing at Detroit, in the county of Wayne and State of Michigan, have invented a new, original, and ornamental Design for Grease-Cup Caps, of which the following is a specification, reference being had therein to the accompanying drawings, forming part thereof, in which—

Figure 1 is a perspective view of a cap

showing my new design; Fig. 2, a side elevation of the same; and Fig. 3, a plan view.

I claim:—

The ornamental design for a grease cup cap, as shown.

In testimony whereof I affix my signature in presence of two witnesses.

ALEXIS R. PRIBIL.
